UNITED STATES PATENT OFFICE

2,602,694

RAILWAY TRACK SERVICING APPARATUS

William Richardson, Pittsburgh, Pa.

Application June 4, 1948, Serial No. 31,194

6 Claims. (CL 299—31)

1

This invention relates to apparatus useful in servicing railway tracks, i. e. in carrying out such operations as air blasting to remove dirt and cinder incrustations from the track rails and from the track beds, and in spraying the rails with grease for protection against rust and for lubrication of joints and bolts.

In connection with such apparatus having the form of a truck with wheels for mobility on the track rails, I aim to provide for propulsion of the truck, operation of an incorporated brake system, spraying both for the purposes of rail cleaning and lubrication, or greasing for rust prevention, and removal and replacement of the apparatus from the rails and vice versa, with the aid of compressed air produced by an internal combustion engine and compressor unit mounted on the truck.

A further aim of my invention is to provide for heating the grease and maintaining it in a fluent condition suitable for the spraying. This latter objective I attain, as hereinafter more fully disclosed, through a simple and reliable means by which the hot exhaust gases from the engine and the hot water are utilized to heat the grease in a supply receptacle wherefrom it is pumped, and by which the exhaust gases are also utilized to heat the grease in a connecting spraying hose for maintenance in a fluent condition, particularly in cold weather.

Other objects and attendant advantages will appear from the following detailed description of the attached drawings, wherein:

Fig. 1 is a view in side elevation of a mobile track rail servicing apparatus conveniently embodying my invention.

Fig. 2 shows the apparatus in top plan.

Fig. 3 is a fragmentary view showing the right hand end elevation of the apparatus as considered in Figs. 1 and 2.

Fig. 4 is a view similar to Fig. 3 with certain parts broken out and others in section, showing the apparatus lifted in readiness for removal from the track rails or for re-railing.

Figs. 5 and 6 are fragmentary views in cross section taken as indicated respectively by the angled arrows V—V and VI—VI in Figs. 1 and 3.

Fig. 7 is a diagrammatic view in top plan showing the compressed air system and mechanism with its controls provided for propelling the apparatus, applying or releasing the brakes and elevating the apparatus in readiness for removal from the rails or for re-railing.

Fig. 8 is a fragmentary detail view partly in top plan and partly in horizontal section taken

as indicated by the angled arrows VIII—VIII in Fig. 1.

Fig. 9 is a fragmentary view partly in end elevation and partly in vertical section taken as indicated by the angled arrows IX—IX in Fig. 2.

Fig. 10 is a horizontal section taken as indicated by the angled arrows X—X in Fig. 9.

Fig. 11 is a fragmentary detail view taken as indicated by the angled arrows XI—XI in Fig. 10.

Fig. 12 is a view in elevation showing a heating element for maintaining the grease in the supply receptacle in fluent condition during the spraying.

Fig. 13 shows means which I have devised to facilitate replacement of the grease receptacle, after it is emptied, by a fresh filled one.

Fig. 14 is a detail section taken as indicated by the angled arrows in Fig. 2.

As herein illustrated, my improved railway track servicing apparatus is characterized by having a horizontal truck platform 10, with side longitudinals 11 and connecting cross members 12, and with two pairs of flanged supporting wheels 13 arranged to run on track rails R, R.

25 Mounted on the platform 10 along one side thereof at one corner, is a power unit 15 which may be of any approved commercial type, with a housing 16 wherein is enclosed a water cooled internal combustion engine and a direct driven air compressor which latter are respectively indicated by the dot and dash line rectangles 17 and 18 in Fig. 2. Compressed air is conducted from the compressor 18 through a pipe line 19 to a storage tank 21 mounted on the platform 10 at the ad-

30 jacent corner immediately rearward of the power unit 15. Superposed upon the air tank 21 is a supply reservoir 22 for the fuel used to operate the internal combustion engine 17. For the propulsion of the truck and for other purposes later pointed out, I have shown an air motor 23, which, through a sprocket chain 25 (Fig. 5), is arranged to drive a power shaft composed of two axially aligned sections 26 and 27, the latter of these sections being in turn connected by another sprocket chain 28 to one of the wheel axles 14 as best shown in Figs. 1 and 2. When the truck is to be run on the track rails R, the section 27 of the power shaft is coupled with the section 26 by means of a clutch 29 arranged to be operated by a hand lever 30. Compressed air is conducted to the air motor 23 from the reservoir 21 by way of piping 31, 31a, 31b (Fig. 7) under control of interposed hand valves 45 and 46 re-

45 spectively at opposite ends of the track. For reversing the motor 23, I have shown a manually 50 controlled valve 47 which, when closed, permits compressed air to be conducted from the reservoir 21 through the piping 31, 31a, 31b to the air motor 23, and which, when 55 opened, permits compressed air to be conducted from the air motor 23 through the piping 31, 31a, 31b to the reservoir 21.

operable valve with hand lever 32. The truck is, moreover, equipped with a brake rigging whereof the shoes 33 (Fig. 1) are pivotally suspended from brackets 34 adjacent the respective wheels 13. By means of toggle bars 35, the brake shoes 33 are connected to a link 36 suspended from a horizontal arm 37 on a transverse rock shaft 38. An upstanding arm 39 also secured to the rock shaft 38 is connected to the piston rod 40 of an air cylinder 41 which is movable about a fixed pivot 42. A spring 43 influential upon the piston of the cylinder 41 serves to normally keep the brakes set. The brakes are automatically released concurrently with starting of the motor 23 by operation of either of the valves 45 or 46 through admission of compressed air into the front end of the cylinder 41 by way of a branch connection 44 extending from a pipe 31b. In order that the brakes may be manually released when necessary or desired, I have provided a hand lever 47 which is loosely connected at 48 to the piston rod 40 of the cylinder 41. As shown the hand lever 47 has a retractable latch rod 49 capable of being engaged with a fixed angle bar 50 on the truck frame 10 when said lever is swung leftward in Fig. 1 to hold the brakes released. The power and brake application mechanism is claimed in a separate patent application Ser. No. 225,243, filed by me on May 8, 1951.

Fixedly positioned on an elevated base 51 at another corner of the platform 10 is an upright open-topped cistern 52 capable of accommodating within it, with substantial clearance all around, a drum 53 containing the grease which is to be used in the spraying of the rails R; and disposed within the cistern is an upwardly withdrawable heating unit which is comprehensively designated 54 in Figs. 9 and 12. At the bottom of the cistern 52 are laterally spaced bars 55 upon which the drum 53 is directly supported with its bottom elevated somewhat above that of the cistern. The heating unit 54 comprises a circumferentially flanged plate 57 which serves as a cover for the drum 53 and from which a pipe coil 56 is suspended. As shown, the turns of coil 56 are secured by means of U bolts 59 to sustaining bars 60 pendent from the cover 57. The ends 56a and 56b of coil 56 extend up through the cover 57, the end 56a being connected to a transversely arranged pipe line 61, 61a which is coupled at 63 to one end of a flexible conduit 64 leading to the water flow outlet 64a on the engine and compressor cooling radiator 65 of the power unit 15. The other end 56b of coil 56 is connected to a pipe 66 which extends diametrically through the lower part of the pressure equalizing chamber 67 of a grease pump later described, said chamber being mounted on the cistern cover 57. As shown, the pipe 67 is continuous with a pipe 68 which, through another flexible conduit 69, is connected to the water return inlet 70 on the cooling radiator 65 of the power unit 15. Within the coil 56, at an elevation somewhat above the bottom of drum 53, is an auxiliary flattened cylindric box-like heating element 75, see Figs. 8 and 9, with a tubular axial core 76 and a diametral baffle 77 which terminates somewhat short of the bottom of said element. Extending down from the cover 57 and connecting into the top of the element 75 respectively to opposite sides of the baffle 77, are flow and return pipes 78 and 79. The terminals of these pipes 78 and 79 also extend through the cover 57, the pipe 78 being directly connected to the cross pipe 61, and the

pipe 79 to a horizontal branch 80 which, in turn, connects with the pipe 66. As a consequence of this arrangement, the flow of the hot water from the radiator 65 is divided to follow courses respectively through the coil 56 and through the auxiliary heating element 75 in the directions indicated by the arrows in Figs. 8 and 9, whereby the grease in the drum 53 is heated to a free-flowing consistency, the flow being controllable by means of the hand valve indicated at 81.

In order to prevent thermal losses by radiation from the grease in the drum 53, the cistern 52 is kept filled with water as conventionally shown in Fig. 9, and the water heated substantially to the boiling point by passage through it of the hot exhaust gases from the engine 17 of the power unit 15. The means relied upon to carry out this function includes two U-shaped tubes 85 which are arranged in parallel relation with their vertical branches 85a and 85b in the circumferential interval between the tank and drum, and with their connecting branches 85c extending crosswise of the bottom of the tank beneath the drum 53. The tubes 85 are joined by a tri-fitting 86 which, through a flexible conduit 87, is in direct communication with the exhaust manifold 88 of the engine 17. The discharge from the terminal ends 85d of the tubes 85 is normally deflected upwardly by the inclined baffle indicated at 89 in Fig. 9.

The heated fluent grease is drawn from the drum 53 by an air operated pump 90 shown as mounted upon the top of the cover 57 alongside the pressure equalizing chamber 67, through a suction pipe 91 which extends down through said cover and through the axial core of the auxiliary heating element 75 to a point slightly above the drum bottom. The pump 90 forces the grease into the pressure equalizing chamber 67 by way of a pipe 92, and discharge of the grease from said chamber takes place through another pipe 93 in which a manual control safety valve 94 is interposed. As shown, valve 94 has a lateral bleed outlet 94a, see Figs. 8 and 9, with a discharge connection down through the cover 57 into the grease drum 53, so that when the pressure in the equalizing chamber 67 exceeds a predetermined degree, the excess grease delivered through the pipe 93 is returned to said drum. The gauge at 95 in Figs. 8 and 9 serves to indicate the pressure at which the grease is delivered. Compressed air for operating pump 90 is conducted to the latter by way of a pipe 96 (Figs. 2, 8 and 9) under control of a throttle valve 97, said pipe being in communication with the air reservoir 21 by way of a hose 93 (Fig. 2). An associated pressure gauge 99 is relied upon to indicate the pressure corresponding to different settings of the valve 97.

For use in the spraying, I have provided a hose 100 which is ordinarily wound upon self-winding reel 101 enclosed in a protective housing 102 on the truck platform centrally of one end thereof, see Figs. 2 and 14. As shown, the hose 100 has a nozzle 103 at its free end, its other end connecting into a hollow in one of the journal bearings 104 of the reel 101 to which the grease is delivered from the outlet pipe 93 leading from the pressure equalizing chamber (Figs. 2 and 8) through an intermediate hose section 105 under control of a hand valve 106. From Fig. 14 it will be observed that the reel 101 is supported on a hollow base 107 which serves as a radiator with 75 in the housing 102. Hot exhaust gases from

the engine of the power unit 15 are conducted to the radiator base 107 by a flexible tube 108 whereof one end is connected to the exhaust gas fitting 86. After traversing the radiator base 107, the hot gases pass off through a vertical exhaust pipe 109 having a muffler 110 at the top. By this arrangement, the grease in the reel hose 100 is kept in a fluent condition at the temperature normally maintained in the grease drum 53. As shown in Fig. 2, a considerable length of the intermediate hose section 105 is normally kept in aligning contact with the gas conduit 108 so that the grease in said section is also kept fluent. Flow of the hot gases through the radiator base 107 of the reel 101 may be interrupted by closing the valve at 111 (Fig. 14) in exhaust pipe 109, so that the entire exhaust discharge from the engine can be employed to heat the water in the cistern 52 for liquification of the grease in the drum 53 in preparation for spraying. After the grease in the drum 53 has been brought to the proper temperature, the hot gas flow may be diverted to pass through the radiator base 107 of the reel housing 102 by temporarily inserting a cut off plate 112 (Fig. 9) behind the inclined baffle 89 so as to stop the discharge ends 85d of the tubes 85. As shown in Figs. 2 and 8, the hose 105 is provided with a coupling 113, and the pipe 98 leading from the air tank 21 to the grease pump 90 with a coupling 98a. By reason of this arrangement, the hose 105 can be disconnected at the coupling 113 and connected to the air pipe 93 at the coupling 98a and said hose then used for blowing grease remaining in the hose 100 back into the grease drum 53 at the end of a day's work. When this change is made, it is of course necessary to close the shut-off valve 106 in the grease delivery pipe 93. In order that compressed air may be utilized to blast off dirt and cinder incrustations from the rails before the latter are sprayed with grease, I provide a suitable length of separate hose which is partly shown at 178 in Fig. 2 and connect it to the air pipe 173 at 179 with interposition of a control valve 180. In practice, the reel housing 102 is so arranged that it can be transposed to the opposite end of the truck as indicated in dot and dash lines at 102x in Fig. 2 for convenience of air blasting from that end of said truck.

As the drum 53 becomes buoyant upon withdrawal of the grease therefrom, it is held against upward displacement in the cistern 52 by a plurality of lashing ropes or cables 115 whereof corresponding ends are secured to a ring 116 engageable with a hook 117 at the side of the cistern near the top. As shown in Figs. 1 and 2, the cables 115 are individually passed downward under guide sheaves 118 on the platform 51 and then upward over guide sheaves 119 adjacent the top of the cistern 52, with loops 120 at their free ends impaled over hooks 121 at circumferential intervals on a removable clamp band 122 surrounding the grease drum 53 at the top.

For the purpose of removing the heating unit 54 in preparation for the substitution of a new filled grease drum for the drum 53 when the latter is empty, I have provided a crane 125 whereof the swivel post 126 is rotatively supported at its lower end in a base bearing 127 at the center of the truck platform 10, and at the top in a bearing 128 sustained by three fixed bracing struts 129. The boom 130 of the crane 125 is adjustable for angularity by a tie member comprising a yoke member 131 which is pivotally connected to the post at 131a and a rod member

132 which is similarly connected to the boom at 132a. The rod member 132 passes through an aperture in the cross bar of the yoke member 131 and terminates in a slide block 133. A pin 135 selectively engageable through holes 136 in the side arms of the yoke member 131 and projectable through a hole in the block 133, serves to secure the boom 130 in angularly adjusted positions. The hook 137 of the crane is suspended from the loop 138 of a lift cable 139 which latter is guided over a system of pulleys 140, 141, 142, 143 and 144, one end thereof being fixedly secured at 145 to the center post 126, and the other end to a winding shaft 146 on the boom which is operable through a sprocket chain connection 147, from another shaft 148 provided with a hand crank 149. When the heating unit 54 is to be withdrawn, the crane hook 137 is lowered and engaged with a ring 150 on a cross piece 151 by which the casings of the pressure equalizing chamber 67 and the air-operated grease pump 90 are connected at the top. With this accomplished, the cable 139 is wound upon the shaft 146 to withdraw the heating unit 54 until it clears the top of the cistern 52, whereupon the boom 130 is swung about to a post 152 upstanding from the truck frame 10 at one end adjacent the cistern 52, and the ring 150 of said unit engaged with the hook end 153 of the arm of said post for temporary suspension therefrom as shown in Fig. 12. While the heating unit 54 is so suspended, a suitable pan (not shown) is placed beneath it to catch the grease drip therefrom. With the heating unit 54 now out of the way, the crane 125 is utilized to withdraw the empty drum 53 from the cistern 52 upon disconnection of the lashing ropes 115. To aid in the latter operation, I have provided a lifting bar 155 which, see Fig. 13, has hook ends to engage projecting ears 156 at diametrically opposite points on the clamp band 122 surrounding the top of the drum 53 and which has a central aperture 157 for engagement by the crane hook 137.

At the remaining corner of the truck is a receptor base 158 for a reserve supply grease drum 53x with a supplemental removable cover 57x from which is suspended a heating coil 56x like the heating coil 56 hereinbefore referred to. As shown in Figs. 2 and 8 the terminal ends of the coil 56x are connected through hoses 159 and 179 to the hot water flow pipes 61a and 80, see Fig. 8, for the heater coil 56 in the drum 53. When the reserve drum 53x is to be substituted for the empty drum in the cistern, the water flow to the coil 56x is shut off by closing the valves at 81a and 81c. The cover 57x is thereupon removed and the band 122 taken from the empty drum and placed around the fresh drum and the crane 125 thereupon used with the yoke 155 to lift the substitute drum from the receptor 158 and place it into the cistern 52. Finally the heating unit 54 is removed from the post 152 and lowered into the new grease drum 53x now in the cistern 52 and the empty drum 53 placed in the receptor 158.

The improved mechanism which I have devised to facilitate removal and replacement of the truck from and upon the rails R includes a pair of skid bars 160 which are shown as formed from suitable lengths of heavy piping and arranged transversely of the truck, one adjacent each end thereof. As instanced in Figs. 3 and 4, an upright tongue 161 is secured centrally of the top of each bar 160, and said tongue slidably engaged in a guide 162 bolted or riveted to the corresponding

end beam 12 of the truck frame. Actuation of each bar 160 is effected by a pair of vertically arranged double acting air cylinders 163 which, see Fig. 6, have trunnions 165 engaged in fixed bearings on the truck frame 10, and which have their piston rods 168 pivotally connected at 169 to such bar somewhat inward of its ends. When air is admitted to the upper ends of the cylinders 163, it will be seen that by action of said cylinders upon the skid bars 160, the truck is lifted to clear the wheels 13 from the rails R, R, as illustrated in Fig. 4. The pivotal mounting of the cylinders 163 and the pivotal connection of the piston rods 168 with the skid bars 160 preclude binding of the parts during the raising or lowering of the truck from or onto the rails. To insure against accidental dropping of the truck either during removal or re-railing, there is associated with each skid bar arrangement a pin 170 which is passed through the guide 162 and into an aperture in the upper part of the tongue 161, said tongue also having a second aperture 171, see Fig. 4, through which the pin is passed to hold the skid bar normally elevated in the clear as in Fig. 3. Each skid bar 160 is limited in its upward movement by stops 172 suspended by brackets from the truck frame 10 at opposite sides, said stops being made to semi-circular cross section to conform with said bars and to snugly receive them as in Fig. 3 so as to prevent them from being bent by impact with obstructions likely to be encountered along the track way. Air is conducted to the opposite ends of the cylinders 163 selectively by way of piping 173 from the reservoir 21 under control of reversible inlet and discharge hand valves 174 whereof one is provided for convenience at each end of the truck. Welded or otherwise permanently secured to the outer ends of the skid bars 160 are caps 175 with clevised projections 176 adapted to be engaged by crow bars such as the one shown at 177 in Fig. 4 by aid of which the re-railing is effected after the truck is lifted from the rails as above explained.

When the exhaust gases from the engine are employed to heat the grease, upward discharge of said gases through the engine exhaust pipe at 88a in Fig. 9 is prevented by a cap 181 which has a manipulating handle bar 182 at the top and a lateral outlet 183. At one side, the cap is formed with an S-shaped cam slot 184 to cooperate with a fixed stud 185 on the exhaust pipe 88a. By giving the cap 181 a partial turn and at the same time lifting it as far as permitted by the slot 184, it can be locked in the raised broken line position in which it is shown in Fig. 9 and so allow the gases to escape through the outlet 183 when heating of the grease is not desired or required.

Having thus described my invention, I claim:

1. In railway track oil spraying apparatus, a wheeled truck with a platform; a receiver on the platform for a replaceable grease drum; a removable cover for the drum; a heating pipe coil extending from the cover down into the drum; a source of circulating fluent heating medium on the platform; flexible tubes extending from said source to the terminals of the heating coil at the drum cover; pump means on the drum cover for drawing heated grease from said drum; and

a flexible spray hose connected to the pump at the drum cover.

2. Spraying apparatus according to claim 1, further including hoist means on the truck for removing drum from the receiver after the grease supply is exhausted and lowering a substitute filled drum into the receiver.

3. In railway track spraying apparatus, a wheeled platform truck supporting separate sources of fluent heating media; an open top cistern on the platform adapted to receive a replaceable grease drum and containing a liquid in which the drum is submerged and completely surrounded; a removable cover for the drum; a heating pipe coil extending down from the cover into the oil drum; tubing surrounding the submerged oil drum in the receiver; flexible conduits extending to the coil and the tubing terminals at the drum cover respectively to the separate sources of heating medium; a pump mounted on the drum cover for drawing heated grease from the drum; and a flexible spray hose connected to the pump at the drum cover.

4. Spraying apparatus according to claim 3, powered by an internal combustion motor of which the water cooling system and the exhaust manifold constitute the different sources of fluent heating medium.

5. Spraying apparatus according to claim 3, further including a housing on the platform for the spray hose; a flexible conduit extending to said housing from the inlet connection of the aforesaid tubing at the drum cover; and means for selectively controlling the flow of heating medium to the coil and the hose housing.

6. Spraying apparatus according to claim 3, further including suction pipe extending down from the pump on the drum cover through the heating coil to a point slightly above the drum bottom; an auxiliary heating element surrounding the lower end of the suction pipe; and piping extending down from the terminals of the coil at the drum cover to said auxiliary heating element.

WILLIAM RICHARDSON.
